SPRAY AND POLISHING HEAD OR SIMILAR ARTICLE

Arnold E. Hanson, Evanston, Ill.

Application July 14, 1950, Serial No. 11,177

Term of patent 14 years

(Cl. D9—2)

To all whom it may concern:

Be it known that I, Arnold E. Hanson, a citizen of the United States and a resident of the city of Evanston, in the county of Cook and State of Illinois, have invented a new, original, and ornamental Design for a Spray and Polishing Head or Similar Article, of which the following is a specification, reference being had to the accompanying drawing, forming a part thereof.

On the drawing:

Figure 1 is a top plan view of a spray and polishing head or similar article, showing my new design;

Figure 2 is a side elevational view thereof;

Figure 3 is a front elevational view thereof; and

Figure 4 is a rear elevational view thereof.

The dotted line showing of a spray or polishing pad is for illustrative purposes only.

I claim:

The ornamental design for a spray and polishing head or similar article, substantially as shown and described.

ARNOLD E. HANSON.
